UNITED STATES PATENT OFFICE.

EUGEN SPEIDEL, OF PFORZHEIM, GERMANY, ASSIGNOR TO FR. SPEIDEL, OF PROVIDENCE, RHODE ISLAND, A FIRM COMPRISING FREDERICK SPEIDEL AND EUGEN SPEIDEL, BOTH OF PFORZHEIM, GERMANY.

ELASTIC MEMBER.

Application filed July 27, 1927. Serial No. 208,891.

This invention relates to an improved construction of elastic member to be used for any purpose for which it is adapted being more particularly designed for use as an elastic band for extendible bracelets, garters, neck bands and the like; and the object of this invention is to construct such an elastic member of more than two lengths of helically coiled members arranged side by side with their coils intermeshing along their length and to position a core in the coils to retain them in intermeshing relation.

A further object of the invention is to form these helical coils with a right and a left hand wind, a length of one wind being positioned between two lengths of the opposite wind and the coils of adjacent lengths intermeshing one with the other and locked against lateral displacement.

A still further object of the invention is in tipping the coils so that each will lie in a plane at an angle to its axis disposing the coils to overlie each other in the manner of fish scales.

With these and other objects in view, the invention consists of certain novel features of construction, as will be more fully described, and particularly pointed out in the appended claims.

In the accompanying drawings:

Figure 1 is a side elevation illustrating my improved elastic member in bracelet form with its ends attached to opposite sides of a wrist watch.

Figure 2 is a short length of helical coil of the left hand wind.

Figure 3 is a helical coil of the right hand wind.

Figure 4 is another helical coil of the left hand wind.

Figure 5 shows the helical coil with right hand wind having helical coils of the left hand wind intermeshing with the opposite edges thereof.

Figure 6 is an end view showing the edges of the two left hand coils as intermeshing with the opposite edges of the right hand coil.

Figure 7 is an enlarged view showing the coils in section with chain cores or members extending through the intermeshing portions of the coils to prevent lateral separation and also showing a central core through the intermediate coil to prevent the side coils from

being pressed inwardly toward each other.

Figure 8 is an end view of the coils as shown in Figure 7 tipped at an angle to overlie each other.

Figure 9 is a side elevation showing the coils as having been tipped to overlie each other in the manner of fish scales.

Fig. 10 is a detail view showing the manner of securing the coils to the attaching sleeve.

It is found of advantage to construct elastic members of this character with more than two helical coils which may be used for the broader type of extendible members and which are designed more particularly to be made into bracelets, garters, neck bands and the like; and it is found of advantage to form such a band or member with sufficient tension when used as a bracelet to be readily extended sufficiently to be passed over the hand of the wearer and at the same time form such a bracelet which is handsome and attractive in appearance; also to provide a bracelet which is extremely simple and inexpensive to construct, the same being made by simply winding a plurality of helical coils, preferably more than two of right and left hand wind, and lay these coils side by side and cause their coils to be intermeshed one with the other along their length; also to position suitable cores or locking members to extend through the intermeshing portions of the coils to hold them against lateral displacement and also in some instances to extend a core through the intermediate coil to prevent the two side coils from being pressed inwardly toward each other; also it is found of advantage to provide a core of such a construction that it will limit the extendibility of the elastic member and so prevent the same from being extended excessively and strained; also it is found of advantage to tip the coils at an angle to their longitudinal axes causing them to overlie each other in the manner of fish scales; and the following is a detailed description of one means by which these advantageous results may be accomplished.

With reference to the drawings, 10 designates a short length of a helical wire coil of a left hand wind which may be made of any desired length and preferably of resilient wire of the desired gauge and wound into 105 coils or convolutions of the desired diameter.

11 designates a similar coil of a right hand wind and 12 another similar coil and of a left hand wind. These different lengths of coils may be formed of different colored wires if desired to render more handsome and attractive the appearance of the bracelet or device which may be made therefrom.

In assembling these coils 10, 11 and 12, they are slightly elongated and the two coils 10 of the left hand wire are forced from opposite sides to intermesh with opposite edges of the intermediate right hand coil 11.

In order to prevent these coils from being disconnected laterally from each other I may 15 position some sort of a core or locking member between the intermeshing portions of these coil members. In some instances I prefer to employ a chain 13 which extends through the intersecting portions of these 20 coils to lock them together also in some instances to prevent the coils from being pressed inwardly toward each other I may employ a central core 14. These cores may be of any suitable material preferably to allow the 25 elastic member to flex and also to extend in a direction of its length. In most instances I prefer to secure one end of these chain cores 13 to the end of the coil or to a sleeve 15 by means of a pin 16, which arrangement 30 effectually protects the device against being ruptured by undue extension.

It is also found of particular advantage in order to enhance the appearance of the plurality of coils as a bracelet or ornamental member to flatten these coils by a set of rolls or dies and so exert pressure upon them sufficiently to tip them over at an angle, as best illustrated in Figure 9 and in some instances to flatten an ornament the top and bottom 35 edges of the wire and the coils and at the same time cause them to present a softer feel to the arm of the wearer.

The foregoing description is directed solely towards the construction illustrated, but I 45 desire it to be understood that I reserve the privilege of resorting to all the mechanical changes to which the device is susceptible, the invention being defined and limited only by the terms of the appended claims.

50 I claim:

1. An elastic member comprising more than two lengths of helically coiled members arranged side by side and the coils of the alternate members intermeshing with opposite sides of intermediate coils, and locking cores in said coils to maintain them in intermeshing relation.

2. An elastic member comprising more

than two lengths of right and left hand helical coils of wire set side by side, the alternate coils being of corresponding wind and intermeshing with opposite sides of a coil of an opposite wind.

3. An elastic member comprising more than two lengths of right and left hand helical coils of wire set side by side, the alternate coils being of corresponding wind and intermeshing with opposite sides of a coil of an opposite wind, and locking cores in said coils to maintain them in intermeshing relation.

4. In an elastic member more than two lengths of helically wound coils arranged side by side with the coils of adjacent length intermeshed one with the other and cores extending through the intermeshed portion of the adjacent coils to prevent a separation thereof.

5. In an elastic member, a plurality of lengths of left and right hand helically wound coils arranged with the length of one wind spaced apart by a length of the opposite wind with the coils of adjacent lengths intermeshed one with the other and cores extending through the intermeshed portion of the adjacent coils to prevent a separation thereof.

6. An elastic member comprising a plurality of lengths of right and left hand helically wound coils lying side by side, a length of one wind being positioned intermediate two lengths of the opposite wind, the coils of adjacent length intermeshing one with the other and said coils being set at an angle to the axes to each overlie a portion of another.

7. An elastic member comprising a plurality of lengths of right and left hand helically wound coils lying side by side, a length of one wind being positioned intermediate two lengths of the opposite wind, the coils of adjacent length intermeshing one with the other, and core members extending through the intermeshing portions of said coils to prevent them from separating.

8. An elastic member comprising a plurality of lengths of right and left hand helically wound coils lying side by side, a length of one wind being positioned intermediate two lengths of the opposite wind, the coils of adjacent length intermeshing one with the other, and a core of chain extending through said members and fastened at its ends to limit the extension of said members.

In testimony whereof I affix my signature.

EUGEN SPEIDEL.
